3 Claims. (Cl. 33—60)

The present invention relates to track aligning systems, and more particularly to track level indicating devices used in such systems.

In track aligning, it is known to establish a line of sight or a reference line vertically spaced from the track rails and to control the alignment of the track in respect of this reference line. The reference line is defined by two reference points which may be fixed or movable in relation to the elongation of the track. The track is aligned by lifting and/or laterally moving the same at a position or positions between the two reference points, and the reference line serves as the guide for determining the lifting and/or lateral moving stroke. For this guidance, there is provided a track level indicating device which comprises a frame adapted to be positioned upon the track rails, an indicating means, such as a marker plate, mounted on the frame and a level indicating edge on the indicating means, the indicating edge cooperating with the reference line to establish the desired guidance.

In conventional devices of this type, the track plane defined by the rails, the frame and the level indicating edge were arranged in the following planar relationship; with the track rails defining a first plane, the frame defined a second plane perpendicular thereto and extending in the same direction as the track rails while the level indicating edge extended in a transverse third plane vertically spaced from the first plane for cooperation with the reference line and perpendicular to the second plane whereby the third plane was always parallel to the first plane.

In a track curve or an arcuate portion of the track, the straight reference line necessarily forms a chord of the arc. The chord is, of course, laterally farther removed from the axis of the track at the center of the arc than at its end points. Thus, if the outer rail is superelevated, the level is incorrectly indicated by the conventional devices because of the larger distance of the reference line from the track.

It is the primary object of the present invention to eliminate this aligning error in track level indicating devices.

This object is accomplished in accordance with this invention by placing at least a part of the level indicating edge, at least when the need therefor arises, in a plane which deviates from the perpendicular in respect of the plane of the mounting frame. The angle of deviation of this plane is at least nearly the same as the angle between the horizontal and the actual plane of the transversely inclined track defined by the track rails in a track curve.

Thus, in the track level indicating device of the invention, the track plane defined by the rails, the frame and the level indicating edge are arranged in the following planar relationship; with the track rails defining a first plane, the frame defining a second plane perpendicular thereto and extending in the same direction as the track rails, and the level indicating edge extending in a third plane vertically spaced from the first plane and transverse to the second plane, the third plane has at least one part enclosing an angle with a fourth plane vertically spaced from and parallel to, the first plane, said angle being at least nearly the same as the angle between the horizontal and the first plane where the first plane deviates from the horizontal.

In a preferred embodiment of the invention, the level

indicating edge inclination is fixed in accordance with the prevailing inclination of the track at curves.

In this preferred embodiment, the indicating means has two like level indicating edge parts rising from a center point and deviating from a plane parallel to the plane of the track by like angles. In this embodiment, either one or the other edge part will cooperate with the reference line, depending on the direction of inclination of the track plane, i.e. the direction of the curve. The center point will cooperate with the reference line when the track plane is horizontal, i.e. when the track runs straight.

The above and other objects, advantages and features of the present invention will be more fully understood by reference to the following detailed description of a preferred embodiment thereof, taken in conjunction with the accompanying drawing wherein

FIG. 1 is a top view of a track curve to be levelled;

FIG. 2 is a schematic end view of a conventional track level indicating device;

FIG. 3 is a similar end view of a track level indicating device according to this invention; and

FIGS. 4 to 6 are similar end views of a specific embodiment of the indicating device according to the invention, shown in operation at track portions with different transverse inclinations.

Referring first to FIG. 1, there is shown a track curve, the track including a pair of rails 1, 1 mounted on ties 2. The end points 4, 4' of the level reference line 5 are located at spaced control points 3, 3' along the track. As is well known in conventional track leveling systems, a desired line of sight or reference line, which may be a wire or a beam of light or other radiation, for instance, is established in a plane vertically spaced from the track rails in any desired manner and the track rails are then lifted in reference to this line. The level indicating means 7 which cooperates with the reference line 5 is shown positioned at location 6 of the track, i.e. at the center of the track arc.

As is known, in a curved track section, the outer rail is higher than the inner rail of the track so that the track plane $x-x$ (see FIG. 3), which is defined by the rails, encloses an angle β with the horizontal. In FIGS. 2 and 3, the inclination of this first or track plane is assumed to be the same at track points 3, 3' and 6, the track 1, 2 shown at the left in these figures indicating the track at mid-point 6 of the curve while the track at the right side of the figures is indicative of the track curve end points 3 and 3'.

As schematically shown in FIG. 2, which merely illustrates the principle of conventional level indicating devices, such devices comprise a frame 9 adapted to be positioned upon the track rails, an indicating means mounted on the frame and a level indicating edge 7 on the indicating means. The frame defines a second plane perpendicular to the first or track plane $x-x$ and the level indicating edge extends in a plane vertically spaced from, and parallel to, the track plane for cooperation with the leveling reference line 5.

It appears from the illustration of track points 3, 3', on the one hand, and 6, on the other hand, in FIG. 2 that, while the track plane inclination at both points is identical, the indicating edge 7 will show an error of the length f in respect of the reference line 5 at point 6 when the edge is parallel to the track plane.

FIG. 3 shows the principle of a level indicating device constructed according to the invention to avoid this error. While the frame 9 is the same as in the device of FIG. 2, the level indicating edge 8 is shown to have one point 11 in a fourth plane $y-y$ (illustrated in broken lines) which is vertically spaced from, and parallel to, the first or track plane while a part of the edge extends in a third plane transverse to the frame plane and enclosing an angle

α with the fourth plane. The angle α is shown to be the same—although it could slightly deviate therefrom—as the angle β between the track plane and the horizontal. Thus, as will be seen from FIG. 3 if a part of the level indicating edge cooperating with reference line or wire 5 is not perpendicular to the frame plane, as in the prior art, the error f at track point 6 is eliminated.

As shown in the schematic illustration of FIG. 3, the indicating device preferably includes two mutually inclined level indicating edge parts, edge parts 8 and 8a ending at center point 11 and the two like parts rising from the center point at substantially the same angle α .

A preferred embodiment of the invention is shown in FIGS. 4 to 6, illustrating a structure incorporating the principle schematically shown in FIG. 3. The three figures show the level indicating device, respectively, at a transversely horizontal position of the track and at two transversely oppositely inclined track positions.

As shown, a track level indicating device is mounted on each rail 1 and the frames 9 of the two devices are interconnected to constitute a preferably mobile chassis which may be readily moved along the track. Each frame 9 has mounted thereon an indicating means constituted by a vertically extending marker plate 10 with mutually inclined level indicating plate edges 8 and 8a. In the track position of FIG. 4, wherein the track is transversely horizontal, the reference line 5 cooperates with the center point of the level indicating edge, which lies in a plane parallel to the horizontal plane of the track. Depending on the transverse inclination of the track at track curves, as shown in FIGS. 5 and 6, the reference line or wire 5 will contact different portions of the level indicating edge 8 or 8a to determine the correct grade of the track in respect of this line.

While the invention has been described in connection with a preferred embodiment, it will be clearly understood that many variations and modifications may occur to the skilled in the art, particularly after benefiting from the present teaching without departing from the spirit and the scope of this invention as defined in the appended claims. More particularly, the specific structure of the level indicating means and the manner of producing the level reference line is totally irrelevant to the principles of the present invention.

What we claim is:

1. A track aligning arrangement including

- (1) a reference line associated with at least one of the track rails and extending in the direction of track elongation vertically spaced from said rail; and
- (2) a track level indicating device associated with said track rail for indicating the level of said rail and comprising
  - (a) a frame positioned upon said rail,
  - (b) an indicating means mounted on the frame and
  - (c) a level indicating edge on said indicating means and engaging the reference line;

(3) the track defining a first plane, the level indicating edge extending in a third plane vertically spaced from the first plane and transverse of a second plane through said associated rail and perpendicular to the first plane, said edge having one edge part enclosing a fixed angle with a fourth plane which is vertically spaced from, and parallel to, the first plane, said fixed angle being at least nearly the same as the angle between the horizontal and the first plane where said first plane deviates from the horizontal, said angles facing in opposite direction.

2. The track level indicating device of claim 1, wherein said level indicating edge has a center point at the intersection of the second and fourth planes, said one part in the third plane rising from the center point at said angle an another part of the indicating edge rising from the center point at the same angle and in the opposite direction.

3. An arrangement for aligning a track having two rails and including

- (1) a reference line associated with each one of said rails and each reference line extending in the direction of track elongation vertically spaced from the associated rail;
- (2) a mobile chassis arranged for ready movement on, and along, said track rails;
- (3) a track level indicating device comprising
  - (a) a frame positioned upon said mobile chassis,
  - (b) a separate and independent indicating means associated with each rail and mounted on the frame, and
  - (c) a level indicating edge on each indicating means and each level indicating edge engaging a respective one of said reference lines; and
- (4) the track defining a first plane, each level indicating edge having two edge parts rising in opposite directions from a center point, each edge part extending in a third plane vertically spaced from the first plane and transverse of a second plane through the associated rail and perpendicular to the first plane, said center point lying in said second plane and each edge part rising from the center point at a fixed angle with a fourth plane which is vertically spaced from, and parallel to, the first plane, said fixed angles being at least nearly the same as the angle between the horizontal and the first plane where the first plane deviates from the horizontal, and the center point being at the intersection of the second and fourth planes.
